SECURING CLIP

Ernest G. Doke, Chicago, Ill., assignor to
MacLean-Fogg Lock Nut Company, Chicago,
Ill., a corporation of Illinois

Application January 28, 1942, Serial No. 428,477

3 Claims.

(Cl. 189—35)

My invention relates to improvements in clips of the character which are particularly adapted for securing certain members of a structure to the supports upon which they rest in overlapping relation, an example of such structure being a railway car floor in which the floor boards are supported by a framework including sills having lower faces offset from the floor boards and adapted to be engaged by the clips which are fastened to the floor boards.

A problem involved in the use of this kind of clip is the accommodation of variable offset spacings between the surfaces of the members to be secured together. In railway car floors, for instance, such variations may occur because of spacing or lack of spacing between floor boards and sill, or differences in sill thickness in different floors or even in different parts of the same floor structure. Heretofore it has been necessary to provide separate clips for each of the various offset conditions that could be anticipated between the clip-engaged surfaces of the floor members. This necessity for a variety of different clip sizes has imposed a substantial burden both upon the clip manufacturer and upon the user.

An object of my invention is to provide an improved securing clip having a novel arrangement enabling a single clip to be used for securing together members having variably offset surfaces, thereby embodying in one selected standard form of clip a range of performance formerly requiring a number of different sizes of clips.

Another object of the invention is to provide such a clip which is capable of thoroughly and reliably securing together a pair of members which may have the spacing between the clip-engaged faces of any incremental variation within a substantial range.

A further object of the invention is to provide an improved securing clip which is particularly adapted for use at a corner formed by angularly related members both of which should be engaged by the clip.

An additional object is to provide a clip which is especially reenforced to permit the use of relatively thin sheet metal in its construction.

Another object is to provide improved nut locking means for clips of this type.

Still another object of the invention is to provide a securing clip of the foregoing general character which is adapted to be made easily and economically from flat sheet metal stock by a simple quantity production stamping process.

Other objects and advantages of my invention will appear more fully from the following de-

scription and from the accompanying drawings, in which similar characters of reference indicate similar parts throughout the several views.

Figure 1 is a fragmentary vertical sectional view through a floor structure showing, in side elevation, a securing clip embodying the features of the invention;

Fig. 2 is a perspective view of the clip;

Fig. 3 is a fragmentary plan view of one face of the clip;

Fig. 4 is a transverse sectional view through the clip showing the use thereof in connecting a floor board to a sill of intermediate thickness;

Fig. 5 is a bottom plan view showing a modification of my clip;

Fig. 6 is a fragmentary sectional view through the floor structure showing the clip of Fig. 5 in side elevation;

Fig. 7 is a fragmentary vertical sectional view taken substantially in the plane of line 7—7 of Fig. 6;

Fig. 8 is a bottom plan view of a modified form of the clip;

Fig. 9 is a bottom plan view of a further modified form of the clip;

Fig. 10 is a side elevation of the clip shown in Fig. 9;

Fig. 11 is a perspective view of another form of the clip;

Fig. 12 is a side elevational view of still another modification;

Fig. 13 is a bottom plan view of the modified clip of Fig. 12;

Fig. 14 is a bottom plan view of another form of the clip including a nut locking device;

Fig. 15 is a transverse sectional view taken substantially along the line 15—15 of Fig. 14; and

Fig. 16 is a transverse sectional view through a further modification having integral nut locking means.

Referring more particularly to the drawings, a clip 10 is shown in Figs. 1 to 4 secured, by way of illustration, to the underside of a member such as a floor board 11 by fastening means which may comprise a bolt assembly 12 including a nut 12a. The clip 10, in turn, secures the floor board 11 to a supporting member or sill 13 upon which the board rests in overlapping relation with its lower face offset from the lower face of the sill.

The section of a floor construction chosen for illustration may be of the type found in railway cars in which wooden flooring is supported by a steel framework. Thus, the sill 13 comprises the

lateral or horizontal flange of a floor frame beam 14 or of some other appropriate part of the supporting framework.

The spacing between the floor board 11 and the clip-engaged surface of the sill 13 may vary in different car floors or even in different sections of the same floor due to differences in sill thickness or other causes. This creates a problem of attaining proper bearing or hold of the portions of the clip which respectively engage against the floor board and the sill. The common expedient for meeting this problem has been to supply clips especially constructed with differently offset portions to accommodate each dimensional requirement.

A feature of the clip 10 is the construction which makes it self-sufficient for accommodating a substantial range of variations in the offset of the board and sill surfaces. The body of the clip includes a floor-engaging portion or base 15 which is formed with a substantial preferably flat engagement face 16. Integral with the base 15 is a frame- or sill-engaging portion or flange 17 having a sill-engaging face 18 offset from the board-engaging face 16 in such a manner as to bear adequately against the opposed lower surface of the sill 13 even though the offset spacing of the latter from the board may vary within a substantial range.

Such variation in the offset spacing between the board and sill surfaces may come about, for example, because of differences in thickness of the sill 13. This thickness may vary from a minimum, such as approximately one-quarter of an inch, as shown in full line at the left side of Fig. 1, to a maximum thickness of approximately one-half of an inch as indicated in phantom outline at 13^a at the right side of Fig. 1. For accommodating the resulting extremes in offsetting, the sill-engaging flange 17 is preferably formed with a plurality of sections in which the face 18 is correspondingly offset from the face 16. Thus, a minimum offset section 19 at one side of the clip is adapted for engagement with the sill 13 where it is of minimum thickness, and a maximum offset section 20 is provided at the opposite side of the clip for engaging the thicker sill 13^a. The flange sections 19 and 20 may be formed in substantially parallel planes so as to secure utmost bearing upon the engaged surface of the sill.

In order to adapt the sill-engaging flange 17 for use with sills of incremental variations in thickness between the minimum and maximum sill thicknesses described, the sections 19 and 20 may be joined by integral slanting-surfaced adapter sections 21. By way of example, Fig. 4 shows a sill 13^b of an intermediate thickness, such as approximately three-eighths of an inch, engaged by one of the slanting adapter sections 21.

All of the structural features and advantages of the clip 10 may be secured by simply and economically stamping it from a suitable gauge of mild sheet steel, the original blank or body from which the clip is formed being in the form of a round disc. The base 15 may be pressed from the center of the body in the shape of a cup-shaped boss which is integrally connected by a generally axially extending annular wall 22 to the sill-engaging flange 17. Thus, the flange 17 encircles the base with the face 18 at a generally tilted angle relative to the face 16 and permits ready and convenient selection of the

particular area of the face 18 which is to be placed in engagement with the sill.

A result of the embossed construction of the clip 10 is that the annular connecting wall 22 provides an efficient reinforcement. This permits the clip to be made of relatively thin material.

The transverse internal dimensions of the cup-shaped recess defined by the base boss 15 is preferably great enough to accommodate a tool such as a wrench used in driving the nut 12^a of the bolt. The shank of the bolt 12 is received in centered relation within the base recess through a central aperture 23.

Turning of the clip, due to the various twisting strains to which it may be subjected in the railway car floor, may be prevented by means such as prongs 24 projecting beyond the face 16 so as to be driven into the floor board 11 in drawing the clip up tight against the latter. This will effectively hold the clip against any tendency toward rotation or turning out of place. In the preferred form the prongs 24 are struck directly out of the metal of the base 15 (Figs. 1 and 3).

In the course of drawing the clip up tightly against the floor board 11 and the sill 13, the somewhat yieldable nature of the metal stock from which it is made, will give enough to allow for slight variations in or between the engaged surfaces. This is particularly true in the instance where one of the slanting adapter sections 21 is employed to engage the sill 13^b. Thus, the engaged portion of the section may give or flatten out somewhat against the sill, as indicated in Fig. 4, under the drawing-up pressure so as to increase its hold on the sill, over what it might be if only point contact were made with the sill.

Improved engagement of the adapter sections 21 with the sill 13^b is obtained by severing the flange 17 along lines 25 which will substantially separate the adapter sections from the minimum and maximum offset sections 19 and 20, as shown in Figs. 5, 6 and 7. In the present instance, the lines of severance 25 extend radially at equidistant intervals designed to separate the flange 17 into four equal sections in which the greater area of each section is adjacent the periphery where it is available for sill-engagement. If preferred, or found more desirable for any particular requirement, the lines of severance 25 may be formed at any other angle than radial. It should also be noted that for some purposes it may be desirable to separate the adapter sections 21 into a plurality of sub-sections by means of cuts similar to the lines of severance 25.

As shown in Figs. 6 and 7, when one of the adapter sections 21 of the clip is drawn up against the sill 13^b with the clip in such a rotary position that the minimum offset section 19 clears the edge of the sill, the engaging adapter section will bend transversely into conformity with the engaged surface of the sill. If the lower side of the adapter section 21 fails to meet the surface of the sill, it can be readily bent up thereagainst. As a result, the adapter section bears quite fully and efficiently against the sill.

Instead of forming the clip circular, it may be of rectangular form as shown in the modified clip 21 of Fig. 8. In this form minimum and maximum offset sill-engaging flange sections 28 and 29, respectively, are severed along lines 30 from adapter sections 31, and the adapter sections are each separated by lines of severance 32 into sub-

sections 33. By reason of the rectangular formation of the sill-engaging flange, each of the sections and sub-sections of the flange has an increased sill-engaging area adjacent the corners of the rectangle. The board-engaging portion of the clip 27 is also formed as an embossed, centrally apertured base identified at 34.

If preferred, the adapter sections of the sill-engaging flange of the clip may be pre-formed to different offsets intermediate the minimum and maximum offset sections and in parallel planes. A clip 35 embodying this feature is shown in Figs. 9 and 10 and includes an embossed base 37 which is integrally connected by means of a connecting and reenforcing wall 38 to minimum and maximum offset sill-engaging flange sections 39 and 40, respectively, and to adapter sections 41 and 42 of respectively different, intermediate offsets. All of the flange sections are preferably cut away at their ends by notching out, as indicated at 43. To facilitate formation of the sections radial slits 44 may be cut to extend inwardly from the inside corners of the notches 43 to the connecting and reenforcing wall 38.

Although the clip 35 is shown as having four equally proportioned and uniformly graduated sill-flange sections, the number, size and graduation of the flanges may, of course, be varied as desired.

The modified form of clip 45 shown in Fig. 11, 30 is of generally rectangular form and is adapted to be made by simple square bending of a flat strip of material. This clip has a board-engaging base portion 47 provided with a central bolt aperture 48. The base lies between the minimum and maximum offset sill-engaging flanges 49 and 50, respectively, which are integrally connected thereto by means of substantially right-angular connecting and reenforcing bends 51 and 52, respectively. The spacing between the connecting walls 51 and 52 is pre-determined to afford ample clearance to accommodate a nut-driving tool. If preferred, of course, additional flanges of graduated offset may be provided at the opposite sides of the board-engaging base 47.

The clip 55 shown in Figs. 12 and 13 is simply of round disk form having a circular board-engaging base 57 which is offset by embossment from an encircling sill-engaging flange 58 of substantially parallel plane relative to the board-engaging face of the base. A central bolt aperture 59 is formed in the base 57, and it may also have a rotation-preventing prong 60. The central embossment of the base 57 strongly reinforces the clip. By having the sill-engaging flange 58 entirely around the clip, engagement thereof at the corners formed by converging sill members, or in other places where engagement is desired with angularly related supporting members, is facilitated.

In Figs. 14 and 15 is shown an embossed-base type of clip 65 equipped with means for locking the nut of the fastening bolt against accidental loosening. In this clip a substantially rectangular embossed board-engaging base 67 has an integral, offset encircling flange 68. At the center of the board-engaging base 67 is a bolt hole 69. Because of the generally rectangular form of the base, substantially straight sides are provided which are adapted for engagement with the 70 edge of the sill so that the clip will be held against rotation relative to the bolt.

Within the recess formed by embossment of the base 67 is a nut locking means which may comprise a relatively thin, rectangular metal plate 70 75

lying flat against the inside face of the embossment. A central aperture 71 in the plate registers with the bolt aperture 69. At each side of the plate 70 is a narrow, integral nut-locking tongue 72 which is in part formed from the plane of the plate 70 by means of parallel slits 73 cut inwardly from the edges of the plate to points short of the aperture 71. The free end portion of each of the locking tongues 72 comprises a tip 74 extending angularly to the plane of the plate and outwardly of the recess to facilitate engagement of the locking tongues by a bending tool.

The locking tongues 72 are initially formed to have their main portions or bodies lie in the plane of the plate 70 and with the projecting tips 74 lying at the edge of the plate. Then after the nut of the bolt has been tightened, any selected one or more of the locking tongues may be bent against the adjacent lateral face of the nut substantially as indicated in dot-dash outline in Fig. 15. The nut will thus be effectively held against accidental loosening. However, when it is desired to loosen the nut, the locking tongues can easily be bent out of the way without breaking off, and they can again be bent back into locking position after the nut has been retightened. The number and positions of the locking tongues 72 enables effective locking of the nut in any rotative position that it may take. Even though one or more of the tongues 72 should break off from repeated bending or become otherwise unusable, the remaining tongues will still permit reuse of the device for effectively locking the nut of the bolt. The plate 70 may either be loosely assembled with the clip 65 or may be secured thereto in any suitable manner such as by spot welding.

In the form of the clip identified by the numeral 75 in Fig. 16, integral nut-locking means is provided. The body of the clip 75 may be formed from relatively thin sheet metal with a base 77 in the nature of an embossment offset from an engagement flange 78. The base 77 has a bolt aperture 79 and is adapted to receive the nut of the fastened bolt thereagainst. One or more integral nut-locking elements 80 in the form of bendable tongues are struck directly from the material of the clip, preferably from the base 77 adjacent the area engaged by the nut. There may be any preferred number of the nut locking tongues 80, the arrangement shown being for three equidistantly spaced and extending radially relative to the bolt aperture 79. Through this arrangement the selected one or more of the locking tongues 80 which will most effectively engage the nut in any particular tightened position may be bent against the nut as indicated in dot-dash outline. To release the nut for intentional loosening, the locking tongues 80 are bent back to permit the nut to clear on rotation. The tongues are then adapted to be bent back into locking position after the nut has been retightened.

From the foregoing it will be apparent that the present invention provides a simple and economical clip which is particularly suitable for connecting together structural members of variable relative proportions. Thus, where the clip is used to connect a floor board to a sill, variations in thickness of the sill are readily accommodated merely by presenting the appropriate graduated section of the sill-engaging portion of the clip to the adjacent face of the sill and securing the clip in place. This entirely eliminates the necessity for special clips for various thicknesses

of sill, within at least a substantial range of sill thicknesses.

The embossment of the clip by which the board-engaging base is formed is of substantial reenforcing value and thus permits the use of thinner material than prior clips.

While the invention is susceptible of various modifications, and alternative constructions, I have shown in the drawings, and have herein described in detail certain preferred embodiments, but it is to be understood that I do not thereby intend to limit the invention to the specific forms disclosed, but intend to cover all modifications and alternative constructions falling within the spirit and scope of the invention as expressed in the claims which follow.

I claim as my invention:

1. In a stamped sheet metal clip adapted for securing a floor board to a supporting sill presenting an engagement face offset below the lower face of the board to a selective variable extent within a given range, a body having a central area thereof pressed into the form of an embossment spaced from all edges of the body and providing a flat base to engage flatwise against the floor board, and a sill-engaging flange structure surrounding the base and extending laterally therefrom in graduated offset relation to the board-engaging face of the base whereby different portions of the flange structure are adapted to make face contact with respective sills having unequal offset spacing relative to their associated floor boards, and an annular substantially right-angular integral wall connecting the flange structure and the base and reenforcing and stiffening the same to withstand the stresses and strains in use which would tend to deform and distort a flat piece of sheet metal of equivalent dimensions and gauge, said flange structure comprising an originally solid flange having radial lines of severance separating the graduated sections thereof into units independent of the remaining sections but all connected together

through the medium of the annular reenforcing and stiffening wall which remains solid and fully effective for reenforcing and stiffening the clip as a whole and each of the separate offset flange sections individually and collectively.

2. A clip consisting of a one-piece hat-shaped metal member of substantially uniform thickness throughout its crown portion and its rim portion; the crown portion being rigid and having a centrally apertured flat top and an interior sufficiently large to receive a nut and the nut-engaging portion of a tool for wrenching the nut upon a bolt entering the crown portion through its top aperture; the rim portion comprising a first pair of diametrically opposite sections disposed in planes substantially parallel with but at different distances from the plane of the crown top, and a second pair of diametrically opposite sections extending between the sections of the first pair and disposed in planes oblique to the plane of the crown top, said rim portion being substantially less rigid than the crown portion and capable of adapting itself to a sill or the like with which any of its aforesaid sections is forcibly engaged by nut-and-bolt pressure applied to the crown portion.

3. A clip consisting of a one-piece hat-shaped metal member of substantially uniform thickness throughout its crown portion and its rim portion; the crown portion having a centrally apertured flat top and an interior sufficiently large to receive a nut and the nut-engaging portion of a tool for wrenching the nut upon a bolt entering the crown portion through its top aperture; the rim portion comprising a first pair of diametrically opposite sections disposed in planes substantially parallel with but at different distances from the plane of the crown top, and a second pair of diametrically opposite sections extending between the sections of the first pair and disposed in planes oblique to the plane of the crown top.

ERNEST G. DOKE.
